UNITED STATES PATENT OFFICE.

HENRY A. WISE WOOD, OF NEW YORK, AND JOHN A. ISBELL, OF MIDDLETOWN, NEW YORK, ASSIGNEES, BY MESNE ASSIGNMENTS, TO WOOD NEWSPAPER MACHINERY CORPORATION, OF NEW YORK, N. Y., A CORPORATION OF VIRGINIA.

TENSION AND REGISTER ADJUSTING MECHANISM FOR WEB-ROLLS.

1,325,551.

Specification of Letters Patent. Patented Dec. 23, 1919.

Application filed June 5, 1913, Serial No. 771,855. Renewed June 10, 1919. Serial No. 303,255.

To all whom it may concern:

Be it known that we, HENRY A. WISE Wood and JOHN A. ISBELL, citizens of the United States, said Wood residing at New York, county and State of New York, and said ISBELL residing at Middletown, in the county of Orange and State of New York, have invented a new and useful Tension and Register Adjusting Mechanism for Web-Rolls, of which the following is a specification.

This invention relates to improvements in the means for adjusting the tension and register of paper rolls on web printing presses. In operating presses of this character it is customary to have men stationed directly by the paper roll for the purpose of regulating the tension brake on the paper roll spindle and the side adjustment of the paper roll to bring it into proper register. These men, of course, are not in position to view the whole operation of the press.

The principal object of this invention is to provide a simple and convenient means for bringing all these adjustments to one central point where they can be controlled by one man so located that he can view the whole operation of the press and so that the control will be easy and simple.

The invention also involves other improvements in details of construction and combinations of parts as will appear hereinafter.

Reference is to be had to the accompanying drawings, in which—

Figure 1 is a side elevation of a portion of the end of a web printing press showing one way in which this invention can be applied thereto;

Fig. 2 is an enlarged detail side elevation partly in vertical section of mechanism pertaining to one of the web rolls;

Fig. 3 is a plan of the parts shown in Fig. 2;

Fig. 4 is an elevation partly in central vertical section of one of the operating columns;

Fig. 5 is a plan partly in section of a hand wheel for one of the operating rods;

Fig. 6 is a sectional view on the line 6—6 of Fig. 1 on enlarged scale;

Fig. 7 is a side view of one end of one of the operating shafts; and

Fig. 8 is a similar view of the other end thereof.

The invention is shown in these drawings as applied to a four-deck printing press, only two of the decks appearing however. This press is shown as having a frame 10 on which are mounted brackets 11 of any desired kind, four for each deck of the press, except the bottom deck which is provided with roll supports on which one of the rolls can be moved directly from the floor. A web spindle A is shown as provided with a bearing B which rests on the bracket 11 and with a brake drum C having a groove D at one end.

On each of the brackets 11 is a lateral projection 12 provided with a vertical stationary arm 13. Pivoted to this is a lever 14 on which is a pin 15 and a socket 16. Adapted to hang from this socket is an adjusting device comprising a pair of bolts 17 having right and left hand threads, and a turn-buckle 18 operated by a hand wheel 19. A spring 20 is provided for engaging in notches in the edge of the hand wheel to hold it in adjusted positions. Lock nuts 21 are provided also for tightening the parts and securing the adjustment. On the top of the adjusting device is a pivoted latch 23 for engaging in the depression 16. The bottom of this turn buckle is pivoted to the end of a lever 25. The two levers 14 and 25 are provided with brake shoes 26.

The inner end of the lever 25 is provided with a fork 27. This fork embraces an operating rod 30^a. On this operating rod is adjustably fixed a collar 31 by means of which pressure can be applied to both of the brake shoes 26 by lifting the rod 30^a. The projection 12 is formed with a cup 32 thereon holding a spring 33 which presses against a nut 34 adjustable up and down on the collar 31. This spring presses up against the nut and by moving the nut up or down on the collar a delicate adjustment

of the brake pressure can be obtained. This spring 33 also tends to counter-balance the weight of the vertical tube 30^a. The nut 34 can be fixed in adjusted position by 5 a screw 35 thereon.

On the projection 12 also is located an emergency brake cylinder 40. It is provided with a piston 41 and a piston rod 42. This piston rod engages the lower brake 10 beam 25, and is connected with it by pivot pin 43. To operate the emergency brake air or other fluid is admitted to the cylinder 40 through an inlet 44 controlled from any convenient point on the machine. The 15 piston is immediately given an upward motion, clamping the brake shoes firmly against the brake drum C. This can be used in case of emergency or when the machine is stopped. It operates independently 20 of the operation by the rod 30^a, so that the adjustment of that rod need not be disturbed when the emergency brake is applied.

On the rod 30^a is a spiral gear 50 meshing with a similar spiral gear 51 supported on a 25 stud 52 fixed to the arm 13 at one end, and to the bracket 11 at the other end. This stud is provided with a screw 53 on one end and the bore of the gear 51 is screw-threaded to fit the same. Connected with the gear 51 is 30 a disk 54 adapted to enter the groove D. It will be seen, therefore, that the rotation of the rod 30^a will rotate the gear 51 on the fixed screw and move it longitudinally of the stud 52. This moves the brake drum 35 and paper roll spindle for registration. It is obvious, therefore, that by a slight rotation of the rod 30^a the register of the paper can be adjusted without disturbing the pressure of the brakes; that the tension of the 40 web can be regulated independently by the rise and fall of the same rod 30^a; and that both of these operations are entirely independent of the emergency brake cylinder which can be operated without changing the 45 adjustments.

The parts so far described relate only to a single one of the web rolls. It will be understood that ordinarily two web rolls are mounted on the machine for each deck. In 50 this case the rod 30^a is shown as provided with two mechanisms for operating two web rolls simultaneously, only one of them of course, being in use at a time. For the purpose of operating the web rolls of the other decks duplicate sets of the mechanism are provided. The other sets are operated by rods 30, 30^b, 30^c. The rods 30, 30^a, 30^b and 30^c, are made hollow, and they are housed one within another. The rod 30 which 55 operates the web rolls of the first deck terminates at a point just above the first deck, and so on. At the bottom each inner rod projects a little below the end of the one containing it.

For the purpose of operating these rods so 65 that each one of them can be either turned or raised independently of each other, the following mechanism is provided. At a point convenient for an operator standing in a position to watch the whole operation of 70 the press are two stationary operating columns 60 and 61. Extending down through one of these columns 60 are hollow operating shafts 62, 62^a, 62^b and 62^c. These shafts are arranged one within the other 75 as is the case with the rods 30, etc. Each inner one projects above the one outside it at the top and below it at the bottom. This affords a convenient way of fixing a series of hand wheels 63, 63^a, 63^b, and 63^c to the 80 upper ends of these shafts for turning them for the purpose of adjusting the tensions of the several web rolls. At the bottom each of these shafts is provided with a worm 64. These worms mesh with and operate a series 85 of worm gears 65, 65^a, 65^b, and 65^c, respectively. Each of these worm gears is mounted on a horizontal hollow shaft 66, on the other end of each of which is an eccentric 67. Each eccentric operates a lever 68 pivoted 90 at 69. This lever has a roller 70 entering a groove 71 in a collar 72 fixed to the operating rod 30. Consequently the adjustment of any one of the hand wheels on the column 60 will rotate its corresponding hollow shaft 66 and the eccentric thereon, so as to operate the lever 68 and raise or lower the rod 30, 30^a, 30^b or 30^c, as the case may be. This regulates the brake pressure and the tension of the web on that deck of the 95 press.

The other column 61 is provided with a similar series of hollow shafts 73, 73^a, 73^b, 73^c, and hand wheels 74, 74^a, 74^b, and 74^c. Each of these shafts is provided with a 100 worm meshing with one of a series of worm gears 76, 76^a, 76^b, and 76^c on a corresponding series of horizontal shafts 77 which pass through the shafts 66 and extend beyond them at each end. On the other end each of 105 these shafts is provided with a spiral gear 78, these meshing respectively with a series of spiral gears 79, 79^a, 79^b, and 79^c, each located on one of the collars 72 which has been described. Each of these collars is 110 keyed to one of the rods 30, etc., so that the adjustment of one of the hand wheels 74, etc., will rotate one of the rods 30 a corresponding distance and adjust the register of the web roll. The spiral gears 50 and 51 115 have teeth at the same angle as the spiral gears 78 and 79. Consequently any vertical movement given the tube 30 by operation of the tension adjustment will give a slight circular movement to that tube without disturbing the register adjustment. It will be 120 obvious also that the roller 70 prevents the tension adjustment from moving when the 125

tube 30 is given a rotary movement by the register adjustment.

Each of the hand wheels is provided with notches 80 and with a spring-pressed pin 81 for holding it in its adjusted positions.

It will be seen, therefore, that the man who regulates the tension of the rolls and the side register does not have to stand at the end of the press as at present, but he 10 may stand up near the folder where all of the webs and folded products pass under his eye. Moreover, by the use of the two tension devices for each deck, one for setting and the other for emergency, each independent 15 of the other, it will be seen that the adjustment of the ordinary tension setting device can be maintained when the emergency device is operated. Thus, after the emergency device has been restored to normal position, 20 the press can be started up again and the adjustment of the tension device will be the same as before. The register also will be maintained.

Although we have illustrated and described only a single form of the invention and shown it as applied to a single type of press, we are aware of the fact that it can be applied to other types of presses and presses of other numbers of decks with 30 equal facility, and that modifications can be made in the details of construction and arrangements of parts without departing from the scope of the invention as expressed in the claims. Therefore, we do not wish 35 to be limited in these respects, but what we do claim is:—

1. The combination with a web roll having a brake wheel, and a pair of brakes adapted to engage it, of two levers to which 40 said brakes are connected, means connecting said levers, a longitudinally reciprocable rod, a collar adjustably fixed on the rod for operating one lever to apply the brakes and yielding means for forcing the collar toward 45 the lever which it operates.

2. The combination with a plurality of web roll supports, of a plurality of web rolls each having a brake wheel, and a pair of brakes for engaging it, two levers for each 50 brake wheel to which said brakes are connected, means for adjustably connecting said levers of each pair, a movable rod, and a series of adjustable collars on the rod each in position for operating one lever of each 55 pair to apply the brakes to the respective brake wheels, whereby the several collars can be individually and delicately adjusted, and the rod can be operated for applying all the brakes.

60 3. The combination with a web roll, of a brake therefor, means for adjusting the pressure on the brake to regulate the tension of the web, said means comprising a lever, a movable rod having means for engaging the

lever, whereby when the rod is moved in one 65 direction the lever will be moved to apply the brake, a delicately adjustable member on the rod for transmitting its motion to the lever, and means independent of said tension device for moving said lever and applying 70 the brake to stop the rotation of the web roll without moving the rod or changing the adjustment of said member.

4. The combination with a web roll supporting device, and means acting upon the 75 roll for adjusting the tension of the web, said means comprising a pair of levers adjustably connected together, and a delicately adjustable member for operating one of said levers for moving it toward the web roll, of 80 means independent of said delicate adjusting means for operating the last named lever for releasing the web roll from the action of said delicate adjusting means, stopping rotation of the web roll instantly and for re- 85 storing the levers to normal previously adjusted condition when said independent means has completed its operation.

5. The combination with brakes for a web 90 roll and a system of leverage for operating the brakes, of adjustable means adapted to engage the system of levers for regulating the pressure of the brakes, a cylinder, a piston in the cylinder, and means connected with said piston for moving said lever independently of said adjustable connection, 95 whereby the brakes can be applied suddenly in emergency.

6. In a device of the character described, the combination of a pair of brakes for a web 100 roll, a lever for each brake, means for connecting said levers, whereby when one of them is operated to apply its brake, the other will also be operated to apply its brake, adjustable tension means adapted to press on 105 the first named lever for operating both brakes, and fluid controlled mechanism for operating on the same lever independently of said adjustable means for applying the brakes rapidly without changing the adjustment of said adjustable means. 110

7. In a device of the character described, the combination of brakes for a web roll, levers therefor, means adapted to operate 115 said brakes, said means being adjustable to regulate the tension, and comprising an operating rod, a collar fixed on said rod, an adjusting nut on the collar, a spring engaging said nut, means for supporting the other end of said spring whereby an adjustment 120 can be secured, and fluid controlled mechanism for operating the brakes independently of said tension mechanism for applying the brakes rapidly without changing the adjustment of the tension mechanism. 125

8. In a brake mechanism for a web roll, the combination of a brake lever, a longitudinally movable rod adjacent thereto, a col-

lar on the rod, a nut adjustable along the collar, a spring engaging the nut and normally forcing the nut toward the lever, a cup for holding said spring mounted in stationary position, and means for moving said rod longitudinally to positively operate the brake lever.

9. In a device of the character described, the combination of a brake for a web roll, a lever therefor, a reciprocable operating rod having means thereon for engaging the lever and moving it toward the web roll to apply the brake, and means independent of said rod for moving said lever in the same direction to apply the brake and release the lever from the action of the rod, the last named means being constructed and arranged to leave the lever under full control of the rod after the said means has ceased to operate.
10. In a machine of the class described, the combination of a frame, a plurality of supports thereon for web rolls, a brake mechanism connected with each support, a series of operating rods for said brake mechanisms, certain of said rods being hollow and arranged one inside another but operable independently of each other, a shaft connected with each of said rods for operating it, a plurality of operating shafts connected with the first named shafts individually, the last named shafts being hollow and arranged one inside the other, and hand wheels thereon for rotating the shafts and shifting the rods.
11. In a device of the character described, the combination of a frame, a series of web roll brake mechanisms thereon, a series of hollow operating rods for said brake mechanisms arranged one inside the other, each rod being both rotatable and reciprocable, means whereby when each rod is reciprocated the tension on one of the brakes will be varied, means whereby when each rod is rotated the web roll connected therewith will be shifted longitudinally for registration, a series of hollow parallel shafts, each having means for reciprocating one of said rods, a series of shafts passing through the parallel shafts and each having means for turning one of said rods.
12. In a device of the character described, the combination of a frame, a series of web roll brake mechanisms thereon, a series of hollow operating rods for said brake mechanisms arranged one inside the other, each rod being both rotatable and reciprocable, means whereby when each rod is recipro-

cated the tension on one of the brakes will be varied, means whereby when each rod is rotated the web roll connected therewith will be shifted longitudinally for registration, a series of hollow parallel shafts, each having means for reciprocating one of said rods, a series of shafts passing through the parallel shafts and each having means for turning one of said rods, a series of hollow shafts one inside the other, each connected with one of the first named hollow shafts for rotating it, a hand wheel connected with each of said series of hollow shafts for operating it, a second series of similar hollow shafts one inside the other having hand wheels, each connected with one of the inner parallel shafts for operating it.

13. In a device of the class described, the combination with a series of web roll shafts and a brake mechanism for each web roll shaft, of a series of rods connected with said brake mechanisms, means whereby when one of said rods is reciprocated, the tension of the brake mechanism will be varied, means whereby when one of said rods is rotated one of said web roll shafts will be reciprocated longitudinally, and independent means for reciprocating and turning each of said rods.

14. In a device of the character described, the combination with a web roll shaft and brake mechanism therefor, of an operating rod, means for turning said rod, independent means for reciprocating said rod, means whereby when said rod is turned the web roll shaft will be reciprocated longitudinally, and means whereby when said rod is reciprocated the tension on the brake mechanism will be varied.

15. In a device of the character described, the combination of two web roll shafts and a separate brake mechanism for each one, of an operating rod therefor, means for rotating said rod, independent means for reciprocating said rod, means whereby when the rod is rotated both of said web rolls will be shifted longitudinally, and means whereby when said rod is reciprocated the tension of both brake mechanisms will be varied.

In testimony whereof we have hereunto set our hands, in the presence of two subscribing witnesses.
